US00D510915S

(12) **United States Design Patent** (10) Patent No.: **US D510,915 S**
Horinouchi et al. (45) Date of Patent: **** Oct. 25, 2005**

(54) **OPTOELECTRONIC IC PACKAGE**

(75) Inventors: **Shogo Horinouchi**, Fukuoka (JP);
Hideki Ohyama, Fukuoka (JP)

(73) Assignee: **Matsushita Electric Industrial Co., Ltd.**, Osaka (JP)

(**) Term: **14 Years**

(21) Appl. No.: **29/191,603**

(22) Filed: **Oct. 10, 2003**

(30) **Foreign Application Priority Data**

Jul. 9, 2003 (JP) 2003-019763

(57) **CLAIM**

The ornamental design for an optoelectronic IC package, as shown and described.

DESCRIPTION

FIG. 1 is a top perspective view of an optoelectronic IC package of the present invention;

FIG. 2 is a first side view thereof;

FIG. 3 is a second side view thereof;

FIG. 4 is a third side view thereof;

FIG. 5 is a top view thereof; and,

FIG. 6 is a fourth side view thereof.

The ornamental design which is claimed is shown in solid lines in the drawings. Any broken lines in the drawings are for illustrative purposes only and form no part of the claimed design.
